Filed Dec. 12, 1963, Ser. No. 77,765

Claims priority, application Great Britain July 22, 1963

Term of patent 14 years

(Cl. D58—2)

FIG. 1 is a top perspective view of a package of bottles, showing my new design in assembled form;

FIG. 2 is a front elevational view thereof with the cover removed; the rear being a mirror image thereof;

FIG. 3 is an end elevational view with the cover removed, the opposite end being a mirror image thereof;

FIG. 4 is a top plan view thereof with the cover removed; and

FIG. 5 is a sectional view taken on the line 5—5 of FIG. 2.

The pair of bottles are maintained in close relationship beside the cover (FIG. 1) by an integral pin and socket on each bottle mutually interlocking as indicated in FIG. 5.

I claim:

The ornamental design for a package of bottles, substantially as shown and described.
